Design No. 3,906, dated March 15, 1870.

DESIGN FOR A TRADE-MARK

The Schedule referred to in these Letters Patent and making part of the same

We, WILLIAM PEARSON and PETER HOGOBOOM, of Ripon, county of Fond du Lac, and State of Wisconsin, have invented and produced a new and original Design for a Trade-mark, of which the following is a specification.

Our design consists of a device or picture of a "double universal joint," as formerly used in coupling shafts for machinery, this device or design being within two circular lines, with the words "Universal Boiler Fluid" between the inner and the outer lines; also, with the word "Trade" above and the word "Mark" below the device or picture of the double universal

joint; this trade-mark to be used in advertising a fluid preparation for cleaning steam-boilers, and known as the Universal Boiler Fluid.

We claim as our invention—

The design for a trade-mark, as described and shown.

WILLIAM PEARSON.
PETER HOGOBOOM.
